UNITED STATES PATENT OFFICE.

GEORGE H. PALMER, OF LANSING, MICHIGAN, ASSIGNOR TO DAIL STEEL PRODUCTS COMPANY, OF LANSING, MICHIGAN.

METAL WAGON BODY.

Application filed April 18, 1924. Serial No. 707,418.

To all whom it may concern:

Be it known that I, GEORGE H. PALMER, a citizen of the United States, residing at Lansing, in the county of Ingham and State of Michigan, have invented certain new and useful Improvements in Metal Wagon Bodies, of which the following is a specification.

This invention relates to certain new and useful improvements in metal wagon bodies, having for its objects among others to provide an improved one-piece metal wagon body of that style such as is well adapted for what is known as express wagons, although not necessarily restricted to that type of vehicle, nor is it restricted to the size or use of the wagon.

It has for a further object to provide a strong, light body, the bottom, sides, ends and flanges of which are stamped or otherwise formed from a single piece of steel, or other metal, and the corners tied together to make a very durable and efficient form of wagon body.

Other objects and advantages of the invention will hereinafter appear, and the novel features thereof will be specifically defined by the appended claims.

The invention, in its preferred form, is clearly illustrated in the accompanying drawings, which, with the numerals of reference marked thereon, form a part of this specification, and in which

Figure 1 is a plan view of the blank from which the body is formed.

Figure 2 is a perspective view of a portion of the body, before the corner ties are applied.

Figure 3 is a perspective view of a corner of the wagon body after the corner tie has been applied.

Figure 4 is a bottom plan, on an enlarged scale, showing the corner tie in position.

Figure 5 is a section on the line 5—5 of Figure 4, looking in the direction of the arrows.

Figure 6 is an enlarged perspective view of one of the corner tie pieces.

Like numerals of reference indicate like parts throughout the several views.

Referring to the drawings

1 designates the blank; it comprises the bottom portion 2, the sides 3, the ends 4, and the flanges 5 formed on the ends of the sides 3, all as will be clearly understood from Fig-

ure 1. This blank is stamped out of sheet metal, preferably steel, and then shaped into the form of the body.

In giving the body the shape desired the sides are bent at right angles to the bottom as along the dotted lines 6, and the ends are bent along the dotted lines 7, to form the rectangular body, the flanges 5 being bent over against the ends and there secured by rivets or other means, the rivets, when employed being passed through the openings 8 in the said flanges, the rivets 9 extending, of course, through the ends of the body, as will be evident. The flanges may be soldered or otherwise secured to the outer faces of the ends, and the flanges serve to close the joints at the junction of the sides and ends, as seen in Figure 2. The ends of these flanges may or may not be tapered.

The upper edges of the sides and ends, beyond their junction with the upper ends of the flanges and the corresponding line of the sides and ends are turned over and downwardly as seen clearly in Figures 2, 3 and 5, to form the surrounding rim 10, the upper edge of which may be more or less rounded as seen in Figure 2, to prevent sharp corners, and the width and depth of this rim may be varied as may be deemed expedient.

As seen in Figure 2 the adjacent ends of the side and end flanges are at right angles to each other and of necessity separated. In order to close these spaces and to tie the corners and also to give a finish to the body I employ tie pieces which are so shaped as to complete the continuity of the flanges around the upper edge of the body and give it a neat appearance as well as to materially strengthen the corners of the body. One of these corner tie pieces is seen in Figure 6. It consists of a body portion with members 11 and 12 at substantially right angles to each other and each comprising the parallel side members 13 and 14 and the connecting member 15. At the corner of the member

the curved wall 16 joins the adjacent ends of the members 11 and 12, there being offsets 17 at the points of junction of the said curved wall 16 with the members 11 and 12, for a purpose which will soon be explained. Joining the adjacent ends of the members 15 is a member 18, arc-shaped as seen in Figure 6, joined to the wall 16, as shown and at the inner angle depressed as seen at 19, forming

the opening 20 for a purpose which will soon be evident. The two members 14 extend for only about one half the length of the members 15 as seen in Figure 6 to leave an opening or space between their adjacent ends.

It will be understood that the corner piece seen in Figure 6 is in reversed position from what it occupied when applied to the body corner, it being thus shown for the purpose 10 of better illustration.

Figures 3 and 4 show the corner piece in place. The curved portion 16 fills the corner of the body the adjacent ends of the rim portions of the side and end fitting over the 15 members 11, the ends of which abut against the shoulders formed by the off-sets 17 as will be clearly seen in Figure 3, the members 14 engaging the adjacent walls of the sides and ends as seen in Figure 3, and the 20 metal at the corner of the body being received in the opening 20. The corner piece is welded or otherwise affixed in this position and a strong and neat appearing corner is given to the body. The corner tie braces 25 the sides and ends, it joins the members 10 of the sides and ends and gives a neat appearance at the corner, not only at the edge but at the top. The arc shaped portion 18 being slightly upwardly bulged as shown in 30 Figure 5 brings its upper face at this point on the same plane as the top face of the rim.

Modifications in detail may be resorted to

without departing from the spirit of the invention or sacrificing any of its advantages.

What is claimed as new is:—

1. A corner piece for a metallic wagon body, the same comprising in a single element a body portion, a curved wall with members disposed substantially at right angles to each other and of trough-shape 40 open at the ends, and an arc-shaped member adjoining the adjacent ends of the trough-shaped member and co-extending with the arc-shaped wall, the inner walls of said trough-shaped members having depending 45 flanges, said arc-shaped member having a depression at the junction of the trough-shaped member.

2. A stamped sheet metal wagon body of one piece with integral bottom, sides, ends and surrounding flange and rim at the upper edges of the sides and ends, a corner piece at each corner of said body at the top, each corner piece embodying in a single element a body portion, a curved wall with members at substantially right angles to each other to engage within said rim and having flanges to engage the vertical walls of the body and an arc-shaped member with depression at the angle to cooperate with and 50 receive the corners of the body.

In testimony whereof I affix my signature.

GEORGE H. PALMER.
